UNITED STATES PATENT OFFICE.

WELLINGTON B. WHEELER, OF EL SEGUNDO, CALIFORNIA.

SEMIRIGID AIRSHIP.

Application filed June 8, 1927. Serial No. 197,304.

My invention relates to airships and more particularly to a semi-rigid airship construction and to driving means and controlling means for airships of the dirigible type.

5 The primary object of my invention is to provide a relatively inexpensive airship structure, of the usual dirigible form, having the driving mechanism wholly within the body thereof, so that there is a minimum of 10 resistance to its movement through the air.

A further object is to provide means instead of the usual propellers, for propelling airships and for supplementing the usual steering means in directing their course and 15 changing their position.

A further object is to provide an airship, of the character described and with propelling means as described, which may be steered and maneuvered with exceptional facility.

20 Other objects and advantages will appear hereinafter and while I show herewith and will describe a preferred form of construction, I desire it to be understood that I do not confine my invention to such preferred 25 form but that various changes and adaptations may be made therein without departing from the spirit of my invention as hereinafter claimed.

Referring to the drawings which accompany 30 this specification and form a part thereof:

Fig. 1 is a left side view of an airship embodying the principles of my invention.

Fig. 2 is an enlarged transverse sectional 35 view of the airship, taken through the ring compartment thereof approximately on line 2—2 in Fig. 1.

Fig. 3 is a fragmentary sectional view of 40 the ring frame taken longitudinally of the airship.

Fig. 4 is a further enlarged sectional view of the upper side of the ring frame, showing one of the ventilator pipes and one of the nozzles.

45 Fig. 5 is a sectional view of the ventilator pipe and nozzle, taken on line 5—5 of Fig. 4.

Fig. 6 is a plan view of one of the nozzle control pulleys.

50 Fig. 7 is an enlarged sectional view of the tail end of the airship, the section being taken vertically and longitudinally of the ship.

Fig. 8 is a transverse sectional view of the tail end of the airship taken on line 8—8 of 55 Fig. 7.

The general form of my semi-rigid airship is similar to that of the usual dirigible. Its

framework consists of a single girder 10 running throughout the length of the ship along its lower side, a nose-frame 11 fixed on the front end of the girder, one or more transverse ring frames 12 fixed at intermediate points of the girder, between its front and rear ends, and a tail frame 13 fixed on the rear end of the girder. This framework is made of duralumin, preferably, or similar 60 light metal.

The airship here shown, by way of illustration, has only one ring-frame and the girder is made in two sections, extending from the ring frame toward the front and 70 toward the rear end of the ship. Suitably formed gas bags 14 and 15 are made to fill the space between the ring frame and the nose and tail frames, respectively, and these are laced to said frames in the usual way and are 75 provided with flaps 16 and 17 adapted to extend downwardly on either side of the girder and to be laced along the lower edge thereof, so as completely to enclose it. A control and 80 passenger cabin 18 having walls with projecting panels 19, set at an angle to allow persons to look straight downwardly through them is rigidly attached to girder 10 and ring frame 12 so as to extend somewhat forwardly 85 and rearwardly from the latter.

Ring frame 12 is built up of various parts, suitably tied and braced, to form a rigid circular unit which occupies a longitudinal space in the ship sufficient to accommodate its propelling mechanism. This propelling 90 mechanism consists of a powerful blower 20 driven by a motor or engine 21 directly connected thereto, and a series of radial air conduits 22, preferably four in number, leading from the blower to pivoted nozzles 23 which 95 extend through short ventilating pipes 24, said ventilating pipes being turnable in bearings 25 fixed 90° apart in ring frame 12, one in the upper side, one in the lower side and the other two in diametrically opposite positions in the right and left sides thereof. The lower nozzle and ventilating pipe are 100 extended downwardly through the cabin as at 26 and an extra bearing 27 is fixed in the floor of the cabin to carry the lower end thereof.

The inner ends of the nozzles are fixed in the inner ends of the ventilating pipes, concentrically therewith by radial spacing arms 28, so as to provide annular open spaces 29 110 between them, and right angled bends are made in both nozzles and ventilating pipes,

outside of bearings 25, the bends of the former being opposite in direction to those of the latter, and the former projecting through the latter, so that when the nozzle opening 30 faces backwardly the opening 31 of the ventilating pipe faces forwardly. Openings 31 of the ventilating pipe are partially collapsed so as to form an elongated inlet, as shown in Figs. 2 and 4, and a covering 32 is fixed on the sides of each nozzle and ventilating pipe so that a revolvable fin 33 is formed, with the air inlet at one end and the discharge nozzle at the other end thereof.

Grooved pulleys 34 are fixed on the inner end of each ventilating pipe and cables 35 are run around these and over suitably placed small pulleys 36, downwardly to cabin 18 and around control pulleys 37, placed in the control end thereof. The control pulleys 37 are made of equal size with grooved pulleys 34 and are marked with pointers 38 whereby the position of each nozzle may be determined at a glance.

The usual fins 39, with rudder 40 and elevator 41 are attached to the tail frame 13 of the airship and the rudder and elevator are connected to steering wheels (not shown) in the control cabin, in the usual way, provision being made in the elevator wheel for permitting the elevator to float or swing under the influence of an automatic stabilizer mechanism 42, mounted inside the tail frame. The stabilizer mechanism consists of a transverse pivot shaft 43, having a short crank arm 44, and a long weight arm 45, with a weight 46 on its lower end, fixed thereto, said shaft being pivoted at its ends in uprights 47 which form part of the tail frame. The elevator is attached to a second pivot shaft 48 extending through the tail frame parallel to shaft 43 and in spaced relation thereto, said shaft 48 having a crank arm 49 which is connected to crank arm 44 on shaft 43 by a connecting rod 50. Crank arms 44 and 49 are fixed on their respective shafts so that connecting rod 50 intersects the line of centers of the two shafts and causes them always to turn in opposite directions, whereby elevator 41 is caused to swing downwardly when weight 46 swings forwardly and upwardly when the weight swings rearwardly, according as the airship is inclined in a downward or an upward course.

A transverse bridge 51, with its ends projecting to form observation balconies 52 upon which guns may be mounted, is built within ring-frame 12, above blower 20, said bridge being accessible by steps or a ladder 53 extending from the floor 54 of the ring compartment. A shorter bridge 55 is built in the upper part of the ring-frame and transverse bars 56 are fixed in the vertical conduit 22 to serve as a ladder whereby said upper bridge 55 may be reached from lower bridge 51. A hatch 57 is made in the roof of the ring com-

partment and a ladder 58, extending from upper bridge 55, is fixed in position to give access to said hatch.

The airship is held in position for taking on or discharging passengers by an anchor cable 59, attached to a suitable anchorage (not shown), and an elevator car 60 is suspended on a winch cable 61 adapted to wind on a winch (not shown) which may be connected to engine 21 so as to be operated thereby, said elevator car serving to carry passengers to and from cabin 18, it being understood that an opening is made in the cabin floor so that elevator car 60 may be drawn wholly within the passenger cabin. A snatch-block 62, adapted to run on anchor cable 59, is attached to the top of elevator car 60 so as to hold the elevator car close to the anchor cable as a guide while it rises from the ground or descends from the passenger cabin.

The operation of my airship will be understood most readily by reference to Figs. 2, 3, 4 and 7. Air currents alone, produced by blower 20 and directed by nozzles 23, serve to propel the airship and in a measure to control its course. The power of the blower is such as to produce a strong flow of air through conduits 22 and out of nozzles 23, the air supply for the blower flowing into the ring compartment through ventilator pipes 24. When the nozzles are turned straight backward the reaction of the currents issuing therefrom with the surrounding air causes the airship to move forward, the atmospheric resistance to its progress being somewhat reduced by the inflow of air through the ventilating pipes, caused by the suction of the blower. Each of the nozzles being controlled by a separate pulley, they may be turned individually into positions which will steer the airship in any direction, will stop it and back it up or will swing it about a vertical axis. By directing the two side nozzles downwardly it will be caused to rise, by directing them upwardly it will be caused to descend, by directing both forwardly it may be caused to back up and by directing one forwardly and the other backwardly it may be caused to turn to the right or to the left. The upper and lower nozzles may also be directed toward one side or the other to hold the airship in its course against a side wind or to assist in turning it; or they may be directed forwardly to assist in backing it up.

The rudder 40 and elevator 41 may be operated in the usual way, as supplementary steering means, or the elevator may be allowed to operate automatically as a stabilizer under the influence of weight 46, as suggested in the foregoing description. In the latter case it will be seen that when the airship is inclined upwardly weight 46 swings rearwardly, as indicated by arrow 63 in Fig. 130

7, and causes elevator 41 to swing downwardly so that it tends to lift the tail end of the airship and thus to hold it on an even keel. When the airship is inclined downwardly 5 weight 46 swings forwardly, as indicated by arrow 64, and causes elevator 41 to swing upwardly which action depresses the tail end and again tends to hold the airship on an even keel.

10 It will be seen that the air currents issuing from the several nozzles normally act not only to propel the airship forwardly but also to reduce the skin or surface friction on the sides of the airship back of them. It will 15 also be seen that the active circulation of air within the ring compartment of the airship prevents any accumulation of gas which might cause an explosion.

While the drawings show an airship with 20 only one ring-frame and two gas-bags it is evident that it might be built with two or more ring-frames, suitably spaced, and with three or more gas bags to fit the intervening spaces. The nose and tail frames may 25 also be so constructed as to be readily replaceable in case of injury or destruction by accident.

Having thus illustrated and described my invention, I claim:

30 1. A semi-rigid airship comprising a single longitudinal girder extending along the under side thereof; a nose frame fixed on the front end of said girder, a tail frame fixed on the rear end of said girder, said tail frame 35 being adapted to carry a rudder and an elevator; a ring frame fixed to said girder, between said nose frame and tail frame, said ring frame being adapted to carry propelling machinery; gas-bags fastened between said 40 ring frame and said nose and tail frames and to said girder; propelling means mounted in said ring frame; steering means mounted in said tail frame and a control and passenger cabin attached to said girder, below said ring 45 frame, said passenger cabin having elevator means associated therewith for carrying passengers thereto and therefrom.

2. In an airship, of the dirigible type, a transverse ring compartment built into the 50 body thereof, forwardly of its middle part; a blower mounted in said ring compartment with an engine adapted to drive it; a series of air conduits connected to said blower, said air conduits terminating in pivoted nozzles 55 which project radially from said ring compartment and are bent so that their orifices extend at right angles to the axis of said conduits, and means for turning each of said nozzles about the axis of the conduit which it 60 terminates.

3. In an airship, of the dirigible type, a transverse ring compartment built into the

body thereof, forwardly of its middle part; a blower mounted in said ring compartment with an engine adapted to drive it; a series of 65 air conduits connected to said blower and extended to equally spaced points within said ring compartment; bent nozzles connected to said air conduits so as to be turnable thereon, said nozzles projecting radially from said ring compartment with their orifices extending at right angles to the axis of said conduits; means for admitting air into said ring compartment and means for turning each of 70 said nozzles about the axis of the conduit to 75 which it is attached.

4. In an airship of the dirigible type, a transverse ring compartment built into the body thereof in spaced relation to its front and rear ends; a blower mounted in said ring compartment with an engine adapted to drive it; equally spaced ventilating pipes fixed in 80 four sides of said ring compartment so as to be turnable about radial axis, said pipes being bent outside said ring compartment so that their openings are directed at right angles to said radial axis; air conduits connected to said blower and terminating within 85 said ventilating pipes; bent nozzles connected to said air conduits so as to be turnable thereon, said nozzles being fixed in said ventilating pipes so as to turn therewith and so 90 as to project therefrom with their orifices extending directly opposite in direction to that of the ventilating pipe openings, and means, operable from the control cabin of the airship, for turning said ventilator pipes and said nozzles.

5. In an airship of the dirigible type, a transverse ring compartment built into the body thereof, in spaced relation to its front and rear ends; regularly spaced fins fixed in 100 diametrically opposite positions, vertically and horizontally, in the sides of said ring compartment so as to be turnable about radial axis; ventilating pipes fixed in said fins so as to be turnable therewith, said ventilating pipes being bent so that their openings coincide with one end of said fins and are directed at right angles to their turning axis; a blower mounted in said ring compartment with an engine adapted to drive it; air conduits connected to said blower and to said 105 fins; nozzles attached to said air conduits within said fins so as to be turnable with the latter on the former, said nozzles being bent so that their orifices coincide with the other ends of said fins and extend oppositely in direction from said ventilating pipe orifices, and means, operable from the control cabin of the airship, for turning said fins, nozzles and 110 ventilating pipes.
